SPOON OR SIMILAR ARTICLE

William H. Gerth, New York, N. Y., assignor to Empire Crafts Corporation, Newark, N. Y., a corporation of New York

Application March 3, 1955, Serial No. 34,853

Term of patent 14 years

(Cl. D54—12)

FIG. 1.

FIG. 2.

FIG. 3.

FIG. 4.

FIG. 5.

FIG. 6.

FIG. 7.

Figures 4, 5 and 6 are sections taken on the respective lines 4—4, 5—5 and 6—6 of Figure 1; and

The essential features of my design for a spoon or similar article reside in the configuration of the handle in combination with the particular type of ornamentation as applied thereto.

I claim:

The ornamental design for a spoon or similar article, substantially as shown and described.
